MULTICHANNEL CARRIER TRANSMISSION SYSTEM

Hans Mayer, Berlin-Charlottenburg, Germany,
assignor to Siemens & Halske, Aktiengesellschaft, Siemensstadt, near Berlin, Germany, a corporation of Germany

Application December 12, 1933, Serial No. 701,963
In Germany December 22, 1932

9 Claims. (Cl. 179—15)

The present invention relates to the multiple transmission of information by means of carrier currents, and has for its object to provide an arrangement whereby interchannel interference due to mutual induction is largely eliminated and the frequency bands are squeezed closely together within the frequency range available for transmission purposes, more particularly if multiple transmission of information over cable circuits is involved.

The well-known properties of the means, as for instance filters, designed to separate the different channels of a multiplex system, require that the frequency bands used for the transmission of information and called hereafter useful bands, do not succeed each other directly, but that they be separated from one another by unemployed frequency ranges.

Accordingly to the invention, the useful frequency bands are so distributed within the available frequency range as to enable such of the products of modulation (harmonics, beat frequencies) due to non-linearly working switching units (e. g. valves) as are most disturbing to fall within the afore-mentioned unemployed frequency ranges. The total pass-band is hereby most efficiently utilized, since the control limits can in certain parts of the useful band be made independent of linearity conditions.

According to the invention, this may be attained by a subdivision of the available pass-band into equal band components (operating bands) whose border frequencies are entire multiples of their width and by the allocation, in each of these operating bands, of a single useful band whose width is smaller than that of the operating band.

According to another feature of the invention, the operating bands are obtained by means of a common intermediate frequency, in an intermediate modulation stage producing frequency bands which lie in the same frequency range, these bands being shifted by another modulation to the desired point in the pass-band. In this manner, it is possible to squeeze the operating bands closely together, without the use of filters of excessively sharp tuning. Further details of the invention will be explained hereinafter with the aid of the accompanying drawings.

Fig. 1 represents diagrammatically a system of frequencies in which the useful bands are arranged symmetrically with respect to the operating bands.

Fig. 2 shows diagrammatically a system of fre-

quencies in which the useful bands are arranged asymmetrically with respect to the operating bands.

Fig. 3 schematically shows a wiring diagram according to the invention, Fig. 4 is a diagram showing both transmitting and receiving apparatus and Fig. 5 is a partial diagram illustrating how certain results may be obtained in accordance with my invention.

The diagram Fig. 1 shows that the available frequency range has been subdivided, according to the invention, into eight equal component bands (operating bands) each having a width of 3000 cycles per second, the border frequencies thereof (0, 3, 6, 9 etc. kilocycles) being entire multiples of their width. Within each of the operating bands, there is a useful band (a . . . h) whose width is less than that of the operating band. According to the arrangement illustrated by Fig. 1, I utilize, as useful frequencies, the frequencies between 250 and 2750 cycles per second, that is to say, those of a band of 2500 cycles per second in width, which is entirely sufficient for speech transmission. The portions lying between the several useful bands in the neighbourhood of the afore-mentioned border frequencies constitute the unutilized frequency ranges mentioned above and determined by the properties of the filtering means. At 2^a, 2^b, 2^c, and 2^d I have indicated the frequency range of the second harmonic corresponding to the useful band frequencies a, b, c, and d respectively.

The frequency distribution shown in Fig. 1 embodies the following characteristics of my invention:

(a) Beat frequencies (including harmonics) resulting from the interaction of two frequencies lying exactly in the middle of two adjacent operating bands coincide with the junctions of the adjacent operating bands (border frequencies) and can therefore not interfere with the useful bands.

(b) The same is true of a range in the neighbourhood of the mid-portion of the operating band the width of which range is equal to the distance separating the highest or lowest useful frequency from the neighbouring border frequency.

(c) Beat frequencies resulting from the interaction of border frequencies coincide again with the border frequencies.

(d) The second harmonics of a useful band fall within the range of only two useful bands.

According to the invention, these properties can practically be utilized as follows:

In the useful bands (transmission of speech, multi-channel carrier telegraphy, picture transmission, etc.), it is often necessary to transmit individual frequencies or frequency bands which have an extremely great amplitude, for instance, the ringing frequency in the case of a voice frequency call within or outside the speech range, the synchronizing frequency in the case of picture transmission etc. According to the invention, the useful bands containing these predominant frequencies are arranged so as to cause these latter to fall within the mid-portions of the operating bands, which results automatically in a coincidence of their beat frequencies with the border frequencies and thus prevents them from producing disturbances in the useful bands. In the system shown in Fig. 1, for instance, I should prefer to use a signalling frequency or ringing frequency of 1500 cycles per second in each of the useful bands.

It is furthermore known that in certain useful bands, e. g. speech, even if there exists no predominant frequency, part of the band has a higher mean amplitude than has the rest. With speech such an amplitude peak is found to lie in the neighbourhood of 1000 cycles per second. The invention can also be applied to such a useful band, by locating the frequency corresponding to the peak amplitude, in the mid-portion of the operating band. This offers the special advantage that the points of greatest low frequency amplitude need not be considered in the determination of the control or cut-off limits of the system and that the transmission system can be most advantageously utilized.

In Fig. 2, a different distribution of frequencies is shown as an example. The width of the operating band has been chosen at 4000 cycles per second and the useful bands have been arranged so as to enable in each case such frequencies as correspond to 1000 cycles per second in the speech band, to fall within the mid-portion of the respective operating band (the midpoints of the several operating bands being at 2000, 6000, 10,000 cycles per second, etc.). As contrasted with the system shown in Fig. 1, the useful band is situated asymmetrically with respect to the operating band. The width of each useful band has again been assumed as of 2500 cycles.

The application of the system embodying my invention, offers advantages even if the amplitudes are uniformly distributed over the entire useful band, since the beat frequencies of a definite range are then also made unobjectionable.

The method by which, according to the invention, the useful bands can be shifted to the desired position within the available pass-band is shown in Fig. 3, as an example.

By means of low-pass filters S_{p1} — S_{p8} , the conversations passing through the circuit terminals 1—8 are confined to a frequency range of 2500 cycles per second and then led to the modulators M_{11} — M_{18} respectively. A common frequency f_2 of 3000 cycles per second produces an intermediate modulation and the band-pass filters B_{11} — B_{18} enable the upper side bands of the modulation products to be picked out. These are led to the modulators M_{21} — M_{28} , each of which is also supplied with an additional frequency f_1 — f_8 respectively. In the example illustrated, the frequencies f_2 , f_3 , f_4 are equal to the frequencies f_5 , f_6 , and f_7 respectively, so that the same carrier frequency may be used for each two useful bands. One band of this pair is an upper side band of this carrier frequency, and the other useful band of

said pair is a lower side band of such carrier frequency. According to the example of Fig. 3, the carrier frequencies f_1 — f_8 are harmonics of the intermediate frequency f_2 and may be taken from the intermediate frequency generator, as indicated in the drawings. By means of the band-pass filters B_{21} — B_{28} one of the side bands is picked out of the respective modulation products. 5

As shown in the example, the frequency bands between the two modulation stages have the same 10 frequencies (from 3250 to 5750 cycles). The bands received at the output of the band-pass filters B_{21} — B_{28} have the values indicated in Fig. 3. The filter outputs are combined in the manner shown in Fig. 3 to form two groups, in order to 15 prevent the interconnection of such filters as allow adjacent frequencies to pass. Each group is connected to a special amplifier V_1 or V_2 . Through another amplifier V_3 and a high-pass filter K , the transmission band corresponding to 20 the conversations in the circuits 1—8 is connected to the line L . A channel N including the amplifier V_n and the low-pass filter S_{pn} is designed to transmit a single low-frequency band and is also connected to the line L . In much the same manner, provision can be made for another channel not shown in the drawings, which is derived from the intermediate modulation stage, so that one obtains a pass-band of about 30,000 cycles per 25 second including, altogether, 10 component bands 30 of 3000 cycles per second each.

In Fig. 5 I have indicated diagrammatically one way of producing the result stated above, namely, that the frequency corresponding to the peak amplitude will lie in the mid-portion of the operating band. In Fig. 5 this result is obtained by a shifting of the useful frequency band within the operating band. Specifically the shift amounts to 1000 cycles, corresponding to the showing of Fig. 2 as compared with that of Fig. 1. Fig. 5 shows 40 only the three upper channels 6, 7, 8 of Fig. 3 with their low-pass filters S_{p6} , S_{p7} , S_{p8} and the modulators M_{16} , M_{17} , M_{18} . It will be understood that the elements to the right of said modulators will be the same as illustrated in Fig. 3. In order 45 to obtain the shift of frequency, I have shown an additional modulation stage consisting of the modulators M_6 , M_7 , M_8 in conjunction with the band-pass filters B_6 , B_7 , B_8 together with an additional carrier frequency generator f_0 producing a 50 frequency of 1000 cycles.

At the receiving end, the original frequencies are regained by an analogous process. From the incoming frequency mixture, a frequency band somewhat wider than the operating band under 55 consideration, is picked out by means of normal filters. The addition of the corresponding carrier frequency produces among others a side-band corresponding to the frequency band obtained at the transmitting end by means of intermediate 60 modulation; the border ranges of this side band, however, contain portions of adjacent frequencies, i. e. neighbouring conversations. By means of a filter having a steep characteristic I pick out the prescribed range of the intermediate frequency band, thereby reliably separating the conversations from one another. A second demodulation at 3000 cycles per second, corresponding to the intermediate frequency f_2 at the transmitting end, then enables the original speech band to be 65 obtained in the usual manner. It will easily be seen that at the receiving end as well, a single demodulation would impose very severe demands on the filters which might be difficult to fulfill.

The system under consideration can, of course, 75

also be used for two-way traffic, that is for duplex operation. The channels 1, 2 and 3 can, for instance, be used, according to Fig. 3, for traffic in one direction and the channels 6, 7 and 8 for that in the opposite direction. The idleness or suppression of the channels 4 and 5 is of advantage, as the interval thereby obtained between the two groups is sufficient reliably to separate the directions of speech by means of filters.

10 It may be noted that, in certain cases, it may be recommendable to effect modulation simultaneously at the transmitting end, so as to enable the information to be cyphered (by inversion or the like) for purposes of secrecy.

15 It will be noted that, as shown in Fig. 3, the circuit has a plurality of transmission branches (eight of them in this particular case). To each of these branches, indicated at 1 to 8 respectively, I supply intermediate carrier currents through 20 the modulators M_{11} to M_{18} , said intermediate carrier currents having a definite frequency f_2 (in this case of 3000 cycles). In addition thereto, I supply to the several branches, through the second modulators M_{21} to M_{28} , branch carrier currents the frequency of which is different from the frequency of said intermediate carrier currents but is an entire multiple of said definite frequency f_2 , the frequencies of the additional branch carrier currents being indicated at f_1 to f_8 .

30 In Fig. 4 I have represented a station arrangement including both transmitting and receiving apparatus. 1, 2 and 3 indicate the terminals of three transmitting circuit branches or channels, while 6, 7 and 8 indicate the terminals of three receiving branches or channels; that is, the two groups of three channels each serve for traffic in opposite directions, one group for each direction. The reference characters in Fig. 4 are largely the same as in Fig. 3, and the arrangement is substantially the same. In view of this, detail description of some of the elements of Fig. 4 is deemed superfluous, particularly as legends have been applied to the various elements. It will be noted that the elements M_{16} , M_{17} and 45 M_{18} of the receiving group are not modulators, but demodulators, and the same remark will apply to the elements M_{28} , M_{27} , and M_{28} . Fig. 4 shows a divided or forked circuit arrangement, corresponding to the separation of the transmitting group of branches or channels from the receiving group; thus, V_1 , V_2 , V_3 indicate amplifiers for the transmitting direction, and V_4 , V_5 , V_6 indicate amplifiers for the receiving direction. Fig. 4 also shows the same generator as supplying the intermediate frequency currents (f_2) both to the modulators of the transmitting portion of the apparatus and to the demodulators of the receiving portion.

I claim:

60 1. A multiple transmission system comprising a circuit having a plurality of transmission branches, means for supplying to each of said branches, carrier currents of the same intermediate frequency, means for supplying to each of said branches, branch carrier currents the frequencies of which are different from said intermediate frequency but are entire multiples of said intermediate frequency, and means for passing through said branches, transmission currents in frequency bands each of which is narrower than the interval between two successive entire multiples of said intermediate frequency.

70 2. A multiple transmission system comprising a circuit, means for supplying thereto carrier currents covering a range of frequencies subdi-

vided into a plurality of channels of equal width, the border frequencies of each of these channels being entire multiples of the said channel width, means for supplying to each of the channels of said circuit, transmission currents in useful frequency bands each of which is narrower than the respective channel, modulating means for placing the useful frequency bands within the respective channels, and additional modulating means for determining the position of each of said bands relatively to the borders of such channels.

75 3. A multiple transmission system comprising a circuit, means for supplying thereto carrier currents covering a range of frequencies subdivided into a plurality of channels of equal width, the border frequencies of each of these channels being entire multiples of the said channel width, means for supplying to each of the channels of said circuit, transmission currents in useful frequency bands each of which is narrower than the respective channel, intermediate modulating means having a common carrier frequency for placing the useful frequency bands within the respective channels, and additional modulating means for determining the position of each of said bands relatively to the borders of the respective channel.

80 4. A multiple transmission system comprising a circuit, means for supplying thereto carrier currents covering a range of frequencies subdivided into a plurality of channels of equal width, the border frequencies of each of these channels being entire multiples of the said channel width, means for supplying to each of the channels of said circuit, transmission currents in useful frequency bands each of which is narrower than the respective channel, and a plurality of groups of successive modulating means for obtaining the desired position of each useful frequency band within the respective channel, each of said modulating means subsequent to the first modulating means of each group using a carrier frequency which is an entire multiple of the frequency used by the first of such successive modulating means.

85 5. A multiple transmission system comprising a circuit, means for supplying thereto carrier currents covering a range of frequencies subdivided into a plurality of channels of equal width, the border frequencies of each of these channels being entire multiples of the said channel width, means for supplying to each of the channels of said circuit, transmission currents in useful frequency bands each of which is narrower than the respective channel, and a plurality of successive modulating means, for obtaining the desired position of each useful frequency band within the respective channel, each of said useful frequency bands being a side band of the corresponding carrier frequency.

90 6. A multiple transmission system comprising a circuit, means for supplying thereto carrier currents covering a range of frequencies subdivided into a plurality of channels of equal width, the border frequencies of each of these channels being entire multiples of the said channel width, means for supplying to each of the channels of said circuit, transmission currents in useful frequency bands each of which is narrower than the respective channel, and a plurality of groups of successive modulating means for obtaining the desired position of each useful frequency band within the respective channel, each of said modulating means subsequent to the first modulating means of each group using a carrier frequency which is an entire multiple of the fre-

quency used by the first of such successive modulating means, some of said useful bands being an upper side-band of the respective carrier frequency, while others are a lower side-band of the respective carrier frequency.

7. A multiple transmission system comprising a circuit, a transmission apparatus comprising means for supplying to said circuit, carrier currents covering a range of frequencies subdivided into a plurality of channels of equal width, the border frequencies of each of said channels being entire multiples of said channel width, and means for supplying to each of said channels, through a plurality of successive modulating means, transmission currents in useful frequency bands each of which is narrower than the respective channel, said useful frequency bands being separated from each other by intervals, and a receiving apparatus including means for supplying carrier currents and demodulating means corresponding in number and character to the modulating means of the transmitting apparatus, and also including normal filters in front of the first demodulating means and additional filters, having a considerably greater sharpness of tuning than said first-mentioned filters, located in front of the last demodulating means.

8. A multiple transmission system comprising

a circuit, means for supplying thereto carrier currents covering a range of frequencies subdivided into a plurality of channels of equal width, the border frequencies of each of these channels being entire multiples of the said channel width, 5 means for supplying to each of the channels of said circuit, transmission currents in useful frequency bands each of which is narrower than the respective channel, intermediate modulating means having a common intermediate carrier 10 frequency, and additional modulating means having carrier frequencies which are higher harmonics of said intermediate frequency, each of the useful frequency bands being a side-band of the carrier frequency of the corresponding chan- 15 nel.

9. A method of transmission which comprises supplying to each of the branches of a subdivided circuit, carrier currents of the same intermediate frequency, and in addition thereto, branch carrier currents the frequencies of which are different from said intermediate frequency but are entire 20 multiples of said intermediate frequency, and transmission currents in useful frequency bands each of which is narrower than the interval be- 25 tween two successive entire multiples of said intermediate frequency.

HANS MAYER.
